George C. Heinrich

UNITED STATES PATENT OFFICE

WANDA MERCKELBACH, NÉE WERNER, OF FLUSHING, NEW YORK

BREAST BEAUTIFIER

Application filed September 13, 1927. Serial No. 219,316.

This invention relates to improvements in apparel particularly in body garments, and more particularly in bust holders, and it is the principal object of my invention to provide a device of this character which I call a breast beautifier adapted to produce a slim and well proportioned form bringing the bust back to its natural location without disturbing the natural functions of the body, allowing the lungs to breathe freely and presenting absolutely no obstacle to the free movements of the body.

Another object of my invention is the provision of a bust supporter eliminating the outward showing of an over-developed bust, and a supporter which may be worn upon the bare skin and will not scratch or otherwise injure the same while, when worn with an evening dress for instance, it will allow free bending forward without danger of injury to the wearer, or of pinching the same.

A further object of my invention is the provision of a bust supporter which is durable and simple in its construction, as well as inexpensive in its manufacture, yet comfortable and efficient in its wearing, effects and qualities.

A still further object of my invention is the provision of a bust supporter which is hygienic in every respect and does not in any way prevent free respiration, or movements of the body.

These and other objects of my invention will become more fully known as the description thereof proceeds, and will then be specifically defined in the appended claim.

In the accompanying drawing forming a material part of this disclosure:—

Figure 1—is an inner plan view of my bust supporter, extended.

Figure 2—is a section on line 2—2 of Figure 1.

Figure 3—is a section on line 3—3 of Figure 1.

The bust holder constructed according to my invention consists of a central part 10 constituting the bust holder proper, and can be made of any material suitable for the purpose and in any size and color desired. The material of this part is strengthened by mar-

ginal reinforcing seams 11 or the like and a plurality of inner reinforcing bands 12. My improved breast-beautifier has preferably the form shown in Figure 1 in which the lower part of the central portion is substantially triangularly shaped, as indicated at 13, and formed into a lower point, to which is attached a loop 14 or the like adapted to secure the device to a corset, etc., in order to limit the upward movement of the supporter. 55

To each side edge of the central part a plurality of elastics 15, 15', are attached at one end, the other ends of which are secured to the side parts or wings 16, 16', having upper pointed parts formed by their bevelled upper edges in approximately the middle thereof, and, which at their outer side edges or seams carry hooks 17 and eyes 17', respectively adapted to allow a securing or fastening of the device in back of the wearer. Shoulder-straps 18, 18', are secured at one end to the upper pointed edge of the side wings and at their other ends to the upper outer points of the middle part, at a distance from the side edges thereof. The bust will find its resting place in the middle portions designated 19, 19' constituting breast forms snugly fitting the breasts, engaging and supporting the same as indicated in Figure 2. 75

It will be clear that in this manner I have produced a bust supporter really beneficial to every woman and girl and which will make the figure as slim as possible presenting a beautiful and well proportioned form adapted to produce a good fit of the dresses. The bust supporter constructed according to my invention will not pinch the bust or flatten the same, and will allow comfortable breathing. While the majority of the bust supporters now in use force the bust downward and thus strain the muscles of the breast and give an unnatural appearance around the waistline, my bust supporter does away with all these disadvantages and produces the appearance of a firm bust, and slim contours, thus preventing the bust from standing out prominently. If attached on the body in an evident manner my bust supporter will bring the bust back to its natural location rendering the hanging down of the bust impossible, 95 100

and thus eliminating the appearance of an over-developed bust.

As shown in Figure 1, a strengthening member 20 is sewed onto the lower part of 5 the central member just above the triangular position 13 thereof.

A stiffening band 21 is attached at its tapering ends 22 between the median reinforcing bands 12. Said band is wider at its 10 middle part and serves to hold the bust supporters in their correct places.

It will be understood that I have described and shown the preferred form of my breast beautifier as one example only of the many 15 ways to practically make the same, and that I do not wish to limit myself to the exact form and make shown, but reserve my right to make such changes as come within the scope of the appended claim without departure 20 from the spirit of my invention and the principle involved.

Having thus described my invention, what I claim as new and desire to secure by Letters Patent is:—

25 An undergarment comprising a fabric body having upper and lower portions, the lower portion being tapered downwardly from its sides towards its center the upper portion having extensions tapered upwardly from its 30 sides and center to form upwardly converging edges for the extensions, portions of the upper portion being bulged outwardly to form breast receiving pockets each disposed intermediate the width of one of the extensions and in spaced relation to margins of 35 the upper portion, reinforcing strips extending vertically of the upper portion in spaced relation to each other transversely thereof and converging downwardly, certain of said 40 strips cross pockets intermediate the widths thereof from the apexes of the extensions and others being disposed between the pockets, side wings having their upper ends tapered upwardly elastic strips connecting the side 45 wings with side edges of the upper portion and being spaced one above another, shoulder straps having their ends secured to the apexes of the side wings and extensions of the upper portion of the body, and means to releasably 50 join the side wings at the back when the garment is worn.

Signed at New York in the county of New York and State of New York this 12th day of September A. D. 1927.
